UNITED STATES PATENT OFFICE.

ELMER E. WELLS, OF STOCKTON, CALIFORNIA.

OIL-FILTER FOR GAS-ENGINES.

1,395,069.

Specification of Letters Patent. Patented Oct. 25, 1921.

Application filed July 31, 1920. Serial No. 400,558.

To all whom it may concern:

Be it known that I, ELMER E. WELLS, a citizen of the United States, residing at Stockton, in the county of San Joaquin, 5 State of California, have invented certain new and useful Improvements in Oil-Filters for Gas-Engines: and I do declare the following to be a full, clear, and exact description of the same, reference being had 10 to the accompanying drawings, and to the characters of reference marked thereon, which form a part of this application.

This invention relates to improvements in devices adapted to be installed in connection with the lubricating system of a motor vehicle whereby the particles of foreign matter in the oil will be automatically removed therefrom, and the clean oil again allowed to lubricate the mechanism. 15 20 The form of the device here shown and described is particularly intended for use on Ford power plants, being especially adapted for such. In this type of power plant, the lubricating in the main is a splash system, the oil, in the vicinity of the fly wheel and transmission, being whirled around by the former so that the flying oil will lubricate all parts within reach. 25

This is true, but at the same time, all 30 the particles of grit etc. such as gear-chips, carbon and the like the formation of which can hardly be prevented, are also carried around with the oil and deposited on the bearings and cylinder walls, causing rapid 35 wear and deterioration.

The principal object of my invention therefore is to provide a device which will catch at least part of the oil thrown up by the fly wheel, and will retain the solid particles in the oil, allowing the clean oil to again enter the crank case. 40

Another object is to provide a one-piece structure for the purpose, adapted to be placed in the transmission box and held in 45 place by the cover thereof, being instantly removable on taking off said cover, and necessitating no changes of any character being made to the power plant.

A further object of the invention is to 50 produce a simple and inexpensive device, and yet one which will be exceedingly effective for the purposes for which it is designed.

These objects I accomplish by means of 55 such structure and relative arrangement of

parts as will fully appear by a perusal of the following specification and claims.

In the drawings similar characters of reference indicate corresponding parts in the several views. 60

Figure 1 is a perspective outline of a Ford transmission and adjacent parts, showing my improved filter installed therein.

Fig. 2 is a longitudinal section of the device, detached. 65

Referring now more particularly to the characters of reference on the drawings, the numeral 1 denotes a continuous flange, of the shape and size of the flange 2 on the transmission box 3. This flange is provided with 70 orifices 4 registering with the holes provided in the cover for said box, so that when said cover is bolted down, the flange is firmly held in place.

Formed with the flange and depending 75 into the box 2 at the rear end thereof, is a well 5 from the upper edge of one side of which a shallow and relatively narrow V-shaped trough 6 leads to the forward end of the transmission box. The deepest point 80 of this trough is directly below the inner edge of the side of the flange 1 toward which the upper face of the fly wheel moves.

This trough at its forward end of course has an opening 7 into the fly wheel case 85 below the transmission case flange 2, so as to catch a certain amount of oil thrown up by the fly wheel. This oil then flows to the well 5, since the entire device has a downward and rearward slant, such being the 90 setting of the transmission-case flange.

The solid matter of course settles to the bottom of the well, while the clean oil returns to the case through orifices 8 cut through the walls of the well at a point 95 just below the bottom level of the trough, and preferably being in the forward end of the well, and on the side opposite the trough, so that when the well is full, the oil flowing down the trough cannot continue to flow out directly through the holes without changing its course, thus giving the sediment a chance to settle. 100

The well may be cleaned out whenever necessary by merely removing the transmission case cover, when the filter may be instantaneously removed as a whole. 105

By means of this device, not only are the cylinders and gears kept from being unduly worn by the abrasive effect of the carbon 110

2
and grit, but the somewhat small oil pipes of the lubricating system as provided on the engine are prevented from being stopped up.

5 From the foregoing description it will be readily seen that I have produced such a device as substantially fulfills the object of the invention as set forth herein.

10 While this specification sets forth in detail the present and preferred construction of the device still in practice such deviations from such detail may be resorted to as do not form a departure from the spirit of the invention, as defined by the appended 15 claims.

Having thus described my invention what I claim as new and useful and desire to secure by Letters Patent is:—

1. An oil filter for vehicle-motors comprising a unit member arranged to be removably inserted into the transmission case under the cover thereof and held thereby, and means in said member whereby the oil thrown up by the fly wheel will be deposited 20 therein and any solid particles in the oil collected and held.

2. An oil filter for vehicle-motors comprising a removable well positioned in the transmission case at the rear end and held 30 in position by the cover thereof, and a shallow trough formed with the well and leading from the forward and upper end thereof to the forward end of the transmission case, and on the side thereof toward which 35 the upper face of the fly wheel of the engine rotates.

3. An oil filter for vehicle-motors comprising a removable well position in the

transmission case at the rear end and held 40 in position by the cover thereof, and a shallow trough formed with the well and leading from the forward and upper end thereof to the forward end of the transmission case, and positioned to catch some of the oil thrown from the fly wheel of the engine 45 with the rotation thereof.

4. An oil filter for vehicle-motors comprising a continuous flange adapted to rest on the flange of the transmission case and to be held in place by the cover thereof, a 50 well depending from said flange at the rear end thereof, and a shallow trough extending from the forward end of the well to the forward end of the transmission case, being positioned on that side which will 55 cause some of the oil thrown around by the fly wheel to be deposited in said trough, the well being provided with orifices in the sides below the junction of the trough therewith for the return of the oil to the transmission 60 case.

5. An oil filter for vehicle-motors comprising a well positioned in the transmission case at the rear end thereof, and a shallow 65 trough leading from the forward and upper end of the well to the forward end of the transmission case, and positioned to catch some of the oil thrown from the fly wheel of the engine with the rotation thereof, the well being provided with orifices in the 70 sides thereof for the return of the oil to the case, said orifices being positioned out of the line of flow of oil from the trough.

In testimony whereof I affix my signature.

ELMER E. WELLS.
